UNITED STATES PATENT OFFICE.

CHARLES P. WHITMAN, OF ATHOL, MASSACHUSETTS.

BENCH-DOG.

SPECIFICATION forming part of Letters Patent No. 249,563, dated November 15, 1881.

Application filed September 5, 1881. (No model.)

To all whom it may concern:

Be it known that I, CHARLES P. WHITMAN, a citizen of the United States, residing at Athol, in the county of Worcester and State 5 of Massachusetts, have invented certain new and useful Improvements in Bench Hooks or Dogs; and I do hereby declare that the following is a full, clear, and exact description of the same, reference being had to the annexed 10 drawings, making a part of this specification, and to the letters and figures of reference marked thereon.

Figure 1 of the drawings is a perspective view of my invention with the toothed edge of 15 the bearing-plate in position for use, and Fig. 2 is a similar view with the broad face of the plate in position for use.

The present invention has relation to that 20 class of devices used by carpenters and others which are adapted to be connected to a bench or table, and usually termed "bench-dogs," its purpose being to hold the work while being planed and finished.

Previous to my invention the bench-dogs 25 usually employed consisted of an upright shaft or shank having upon its upper end the dogs, said shaft or shank being vertically adjustable, and also reversible, to bring either the plain or toothed end of the dog in position for use, 30 as circumstances may require.

It is the object of the present invention to 35 improve the construction of this class of devices, whereby the dog is held in position more firmly and effectually, so as to prevent any possible vibrations of the same, and to present 40 a smooth and wide surface to hold the work against while it is being finished, that it may not be bruised or otherwise injured. These several objects I attain by the construction substantially as shown in the drawings and hereinafter described.

In the accompanying drawings, A represents 45 the frame, of suitable metal, which is countersunk or mortised into the bench or table so that its upper surface comes flush with that of the bench or table, the frame being secured thereto by screws or other suitable fastenings. The frame A is cast with a bowl, a, to receive the head of the thumb-screw b, which passes

through said bowl and bears in a groove, c, in 50 a sliding bar, d. This bar d has grooves upon both its sides, and instead of passing down through the frame A in an upright or vertical position, as heretofore, it passes through the frame in a slanting position or at an acute angle, and is held at the desired elevation by the thumb-screw b. The bar d at its upper end 55 has the plate B, one edge of which is formed with teeth e, against which the material to be planed is brought, the screw b firmly holding 60 the bar at any required elevation and in perfect line without the danger of any lateral vibration as the point of the screw enters the groove c in the bar, this being important where fine work is being finished.

When the plate B and bar d is in the position as shown in Fig. 2, a large, wide, and smooth surface of the plate is presented to hold the work against when it is being finished, that it may not be bruised, scratched, or otherwise 70 injured, as would be likely did the edge only of the plate come in contact with the work.

The angle at which the bar d passes through the frame A and held by the screw b and the position of the plate B with relation to the bar 75 are of great importance, the angle of the bar giving an increased leverage power. Hence a slight pressure from the thumb-screw sets the bar solid and holds it firmly in position, there being comparatively little strain or wear on 80 the screw.

Having now fully described my invention, what I claim as new, and desire to secure by Letters Patent, is—

In a bench hook or dog, the combination, 85 with the frame A and thumb-screw b, of the bar d, passing through the frame at an acute angle, and spurs at one end of the plate B, said bar being adjustable and reversible, substantially as and for the purpose set forth.

In testimony that I claim the above I have hereunto subscribed my name in the presence of two witnesses.

CHARLES P. WHITMAN.
